UNITED STATES PATENT OFFICE.

JAMES E. SHRADER, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed October 30, 1918. Serial No. 260,291.

To all whom it may concern:

Be it known that I, JAMES E. SHRADER, a citizen of the United States, and a resident of Edgewood Park, in the county of Allegheny and State of Pennsylvania, have invented a new and useful Improvement in Circuit Interrupters, of which the following is a specification.

My invention relates to circuit interrupters and particularly to arc-extinguishing means therefor.

One object of my invention is to provide means whereby negative ions are prevented from flowing between the contact members of a circuit interrupter when they are separated to thereby extinguish the arc that is drawn.

Another object of my invention is to provide means of the above indicated character that shall be simple and inexpensive to construct and effective in its operation.

In practicing my invention, I provide two cooperating contact members and means for causing streams of air or any suitable fluid to flow from the face of one to the face of the other contact member when they are separated. The streams of fluid prevent negative ions from flowing between the contact members and, since the negative ions predominate in the arc that is drawn, the arc is extinguished.

Figure 1 of the accompanying drawings is a diagrammatic view of a circuit interrupter embodying my invention; and Fig. 2 is a diagrammatic view of a rectifier illustrating the principle of operation of my invention.

A circuit interrupter embodying my invention comprises two cooperating contact members 1 and 2 the contact member 1 of which is connected to the positive conductor of the circuit and the contact member 2 of which is connected to the negative conductor of the circuit. The contact member 2 is provided with a plurality of openings 3 in the face and sides thereof that communicate with a receptacle 4 adjacent thereto. A flexible conduit 5 is connected between the receptacle 4 and a tank 6 containing compressed air or any other suitable fluid. The term air as hereinafter employed is understood to include any suitable fluid. A valve 7 is provided for controlling the flow of air

from the tank 6 through the openings 3 and it, in turn, is controlled by a link mechanism 5 that is actuated when the contact member 2 is moved out of engagement with the contact member 1. That is, the valve 7 is adapted to be opened to permit streams of air to flow from the face of the contact member 2 to the face of the contact member 1 only when the contact members are separated.

It is a well known fact that, if a source of alternating current is connected across the terminal members 10 and 11 of the device shown in Fig. 2 of the drawings and a stream of air is projected from the member 10 against the member 11, the load 12 will be supplied with direct current. That is, the stream of air during one part of the cycle 70 assists negative ions to flow from the contact member 10 to the contact member 11, and, during the other half of the cycle, prevents negative ions from flowing. In other words, since negative ions are permitted to 75 flow only in one direction, the device constitutes a rectifier and the principle of operation may be applied to the direct-current circuit interrupter as shown in Fig. 1 of the drawings.

Since negative ions tend to flow from the contact member 1 to the contact member 2 when the same are separated, the streams of air directed from the contact member 2 prevent the flow of negative ions and thus extinguish the arc that is drawn when the contact members are separated. The openings 3 extend to the sides of the contact member 2 to thus prevent fringing out of the arc and, since the arc cannot be maintained 90 when the negative ions are neutralized, the air pressure serves a double purpose of extinguishing the arc and blowing the arc gases out of engagement with the contact members.

My invention is not limited to the specific structure illustrated, as it may be variously modified without departing from the spirit and scope of the invention as set forth in the appended claims.

I claim as my invention:

1. In a circuit interrupter, the combination with cooperating contact members, of means for directing a stream of fluid normal to the face of the positive contact member whereby the negative ions are precluded

- from flowing and the arc that is drawn, when the contact members are separated, is extinguished.
2. A direct-current circuit interrupter comprising two cooperating contact members and means for directing a stream of fluid from the face of the negative contact member to the face of the positive contact member when they are separated.
- 10 3. A direct-current circuit interrupter comprising two cooperating contact members and means for directing streams of fluid from the face and sides of the negative

contact member, when the contact members are separated, to prevent the flow of negative ions therebetween. 15

4. A direct-current circuit interrupter comprising two cooperating contact members and means for directing a plurality of streams of fluid from the face of the negative contact member to the face of the other when they are separated. 20

In testimony whereof, I have hereunto subscribed my name this 15th day of Oct., 1918.

JAMES E. SHRADER.
